UNITED STATES PATENT OFFICE.

CHARLES WALLACE HUNT, OF NEW YORK, N. Y.

HOISTING APPARATUS.

No. 841,870.

Specification of Letters Patent.

Patented Jan. 22, 1907.

Application filed July 24, 1906. Serial No. 327,487.

To all whom it may concern:

Be it known that I, CHARLES WALLACE HUNT, a citizen of the United States, residing at West New Brighton, borough of Richmond, of the city of New York, State of New York, have invented certain new and useful Improvements in Hoisting Apparatus, of which the following is a specification, reference being had to the accompanying drawings, forming a part hereof.

This invention refers to coal and ore elevators and other forms of hoisting apparatus in which the hoisting-drum is driven by an electric motor. The greatest difficulty experienced hitherto in the use of hoisting apparatus of this character has been in the control of the descent of the load.

It is the object of this invention to make it practicable to employ the resistance offered by the running of the motor backward—as a generator, for example—as a resistance to the descent of the load without liability to the undesirable results heretofore experienced, and this is accomplished by combining in operation a mechanical brake and the electric brake above referred to, the former operating to hold the load in a state of rest and being released as the latter is brought into operation. The mechanical brake is progressively released as resistance of the motor is progressively increased until the mechanical brake is entirely released and the descent of the load is wholly controlled by the resistance of the motor.

The invention will be more fully explained hereinafter with reference to the accompanying drawings, in which a practical embodiment of the invention is illustrated.

In the drawings, Figure 1 is a view in elevation, partly broken out, illustrating a hoisting apparatus equipped with the present improvements. Fig. 2 is a diagrammatic view illustrating particularly suitable electrical connections. Fig. 3 is a detail view illustrating the application of a divided motor-field.

It will be obvious as this explanation proceeds that the invention is capable of application to any form of hoisting or other equivalent apparatus and that a single illustration of the application of the invention has been chosen as a convenient and practical embodiment of the invention, sufficient for a complete understanding of the nature of the invention.

In the apparatus shown in Fig. 1 the load (represented by a bucket *a*, whether full or

empty) is shown as connected by a hoisting-rope *b*, which passes over suitable guide-sheaves *c*, with a hoisting-drum *d*, which in this instance is shown as mounted directly upon the armature-shaft of a suitable electric motor *f*. A controller (represented generally at *g* in Fig. 1) is provided for the motor, and a mechanical brake *h* (shown also in Fig. 2) is provided for the drum *d*, the brake in this instance being represented as applied by a weight *i*, acting in opposition to a solenoid *k*, by means of which, through suitable connections, as hereinafter described, the brake is released.

Current is supplied to the motor from any suitable source. Assuming that it enters at *l*, it is conducted to the movable contact *m* of the controller, and in hoisting is conducted thence through a variable resistance *n'* and connections *n²* *n³* to the field *o* and brushes *o'* and *o''* of the motor *f*. At the same time current is conducted in the arrangement shown by the arm *m'*, contact *p*, and connections *p'* and *p²* to the solenoid *k* and thence by connection *p³* back to the line *l*.

Any suitable arrangement of connections for hoisting and for releasing the brake while hoisting may be employed, this description being more particularly concerned with the operation of the motor during the lowering of the load.

As stated hereinbefore, the line *l* is connected to the movable contact *m* of the controller *g*, and when the parts are in normal position and the load is at rest the movable contact of the controller is in such position as to open all circuits and leave the brake *h* to be applied to the drum *d* by the weight *i* or whatever other device may be employed in its place. There are provided, however, in addition to the variable resistance *n'* two variable resistances *q* and *r*, which are controlled, respectively, by the arms *m* and *m'* of the movable contact. The resistance *q* is higher than the resistance *n'* and is so formed that there is always in series with the motor a sufficient resistance to permit the motor being driven backward by the minimum load at the desired speed. The resistance *q* is connected to the field *o* through the connection *n³*, and the resistance *r* is connected to the solenoid *k* through the connections *n'* and *p²*.

In describing the operation of the apparatus during the lowering of the load it will be assumed, first, that the load is in a state of

rest, with the parts as represented in the drawings, the drum d being held from rotation by the mechanical brake h , operated by the weight i or some other suitable means.

5 If it be desired now to permit the load to descend, the movable contact m m' is shifted so as to close the circuit through the resistances q and r and through the field o of the motor, the connections being such as to 10 cause the motor to act as a retarder or resistance while being driven backward during the descent of the load and to excite the solenoid k in a manner to release or partially release the brake h , the maximum resistance 15 in the electrical circuit being included at the outset, so that there shall be no danger of overheating the motor even if the load does not start at once. The tendency of the load and its effect when moving downward is to 20 revolve the drum d and run the motor backward, thus generating counter electromotive force and opposing the current which flows from the line through the resistance q . Simultaneously the brake is proportionately 25 released through the action of the solenoid, as described, and the combined resistance of the mechanical brake and the retarding effect of the current in the motor being less than the effort of the load to descend the motor is 30 driven backward at a controlled speed by the load as it descends. As soon as a balance is reached between the stress of the load and the action of the partially-relieved brake, together with the resistance offered by the 35 motor to rotation backward, the drum d will continue to be rotated backward at a fixed speed by the action of the load. If the movable contact m m' be shifted farther, cutting out a portion of the resistance q and a 40 portion of the resistance r , the motor will be made stronger, its tendency to resist being driven backward by the load will be made greater, and the opposition offered to being driven backward of the motor under the 45 stress of the load will be increased. Through the cutting out of some of the resistance r the brake h will be further relieved and somewhat in proportion to the increase of resistance offered by the motor to the running 50 backward of the drum; but the relief of the brake in practice is greater than the increase of the current through the motor, so that the speed of descent of the load will increase. The counter electromotive force generated by 55 the motor being driven backward by the load will increase with its speed, and a balance will eventually be attained, so that the load will continue thereafter to descend at a fixed speed, but at a speed greater than that in the 60 first instance. The shifting of the movable contact m m' is continued, if desired, until the whole current passes direct to the solenoid and to the motor, relieving the brake h entirely and leaving to the motor the whole 65 effort to resist the descent of the load.

Instead of leading the line l to the center of motion of the movable contact m m' it might be connected to a fixed contact, as at m^2 , the circuit being completed by the movable contact sweeping over such fixed contact and the resistance-terminals. Furthermore, as the load which is lowered is usually much less than the load which is raised the field of the motor may be divided, if desired, as shown in Fig. 3, a portion only of such field, as o^3 , being in connection with the resistance q for lowering, while the whole field o^3 o^4 may be in connection with the resistance n' for raising the load.

In the embodiment of the invention herein illustrated the motor is represented as a direct-current motor of ordinary type; but it will be understood that any suitable motor which can be made to offer resistance to backward rotation can be employed, as well as that various other changes in details of construction and arrangement can be made to suit different conditions of use, and that the invention is not restricted to the precise construction and arrangement shown and described herein.

I claim as my invention—

1. In an electric hoisting apparatus, the combination of a motor, a hoisting-drum, a mechanical brake, means to decrease the resistance of the mechanical brake, and means to increase the resistance of the motor to backward rotation.

2. In an electric hoisting apparatus, the combination of a motor, a hoisting-drum, a mechanical brake, means to progressively decrease the resistance of the mechanical brake, and means to progressively increase the resistance of the motor to backward rotation.

3. In an electric hoisting apparatus, the combination of a motor, a hoisting-drum, a mechanical brake for said drum, means to decrease progressively the resistance of said brake and permit the load to descend, and means acting to cause said motor to operate with progressive force as a progressive resistance to the descent of the load when running backward during the descent of the load.

4. In an electric hoisting apparatus, the combination of a motor, a hoisting-drum, a friction-brake for said drum, electromagnetic devices to control said brake, means to actuate said devices to release the brake progressively and means acting to cause said motor to operate with progressive force as a resistance to the descent of the load when running backward during the descent of the load.

5. In an electric hoisting apparatus, the combination of a motor, a hoisting-drum, a mechanical brake, means to decrease the resistance of the mechanical brake progressively, variable resistances included in the field-circuit of the motor, and means where-

by the circuit is closed through said resistances to increase the resistance of the motor to backward rotation as the brake is progressively released.

5. In an electric hoisting apparatus, the combination of a motor, a hoisting-drum, an electrically-controlled mechanical brake for said drum, variable resistances included respectively in the field-circuit of the motor and in the circuit of said electrical controlling devices, and means whereby the circuit is closed through said resistances to release the brake and to cause the motor to operate as a resistance to the descent of the load when 10 running backward during the descent of the load, the respective resistances being progressively reduced.

6. In an electric hoisting apparatus, the combination of a motor, a hoisting-drum, a mechanical brake, means to decrease the resistance of the mechanical brake, electrical connections for driving said motor in hoisting and electrical connections for increasing the resistance of the motor to backward rotation 15 during the descent of the load, the whole of the field of the motor being included in the connections for hoisting and a portion only of the field of the motor being included in the connections for increasing the resistance of the motor to backward rotation.

7. In an electric hoisting apparatus, the combination of a motor, a hoisting-drum, a mechanical brake for said drum, means to release said brake and permit the load to descend, electrical connections for driving said motor in hoisting, electrical connections for increasing the resistance of the motor to backward rotation and variable resistances included in the field-circuit of the motor, the 20 whole of the field of the motor being included in the connections for hoisting and a portion

only of the field of the motor being included in the connections to increase the resistance of the motor to backward rotation.

9. In an electric hoisting apparatus, the 45 combination of a motor, a hoisting-drum, a mechanical brake for said drum, electromagnetic devices for controlling said brake, electrical connections whereby said devices are actuated to release the brake, electrical connections for driving said motor in hoisting, and electrical connections for increasing the resistance of the motor to backward rotation, the whole of the field of the motor being included in the connections for hoisting and a 50 portion only of the field of the motor being included in the connections for increasing the resistance of the motor to backward rotation.

10. In an electric hoisting apparatus, the 60 combination of a motor, a hoisting-drum, a mechanical brake for said drum, electromagnetic devices for controlling said brake, electrical connections whereby said devices are actuated to release the brake, electrical connections for driving said motor in hoisting, and electrical connections for causing said motor to operate as a generator when running backward during the descent of the load, the whole of the field of the motor being included in the connections for hoisting and a 65 portion only of the field of the motor being included in the connections to cause the motor to operate as a resistance when running backward.

This application signed and witnessed this 70
13th day of July, A. D. 1906.
